(57) **CLAIM**

The ornamental design for a heating module of an electric griddle as shown and described.

DESCRIPTION

FIG. 1 is a perspective view of a heating module of an electric griddle showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is an exploded perspective view of the heating module of an electric griddle.

The broken lines show portions of the article that form no part of the claimed design.
